CLAIM

The ornamental design for a bird feeder stand, as shown and described.

DESCRIPTION

FIG. 1 is a front perspective view of a bird feeder stand showing my new design;

FIG. 2 is a side perspective view thereof;

FIG. 3 is a top plan view thereof;

FIG. 4 is a bottom view thereof;

FIG. 5 is a front elevation view of the bird feeder stand, the rear being identical; and,

FIG. 6 is a left side elevation view of the bird feeder stand, the right side view being identical.
